(57) **CLAIM**

The ornamental design for a vehicle wheel hub cover, as shown and described.

DESCRIPTION

FIG. 1 is a perspective view of a vehicle wheel hub cover; FIG. 2 is a back perspective view of the vehicle wheel hub cover of FIG. 1;

FIG. 3 is a top view of the vehicle wheel hub cover of FIG. 1;

FIG. 4 is a bottom view of the vehicle wheel hub cover of FIG. 1;

FIG. 5 is a left side elevational view of the vehicle wheel hub cover of FIG. 1;

FIG. 6 is a right side elevational view of the vehicle wheel hub cover of FIG. 1;

FIG. 7 is a front elevational view of the vehicle wheel hub cover of FIG. 1;

FIG. 8 is a rear elevational view of the vehicle wheel hub cover of FIG. 1;

FIG. 9 is a cross-sectional view of the vehicle wheel hub cover of FIG. 1, sectioned along line 9-9 in FIG. 7;

FIG. 10 is a cross-sectional view of the vehicle wheel hub cover of FIG. 1, sectioned along line 10-10 in FIG. 7;

FIG. 11 is a front perspective view of a second non-limiting embodiment of a vehicle wheel hub cover;

FIG. 12 is a back perspective view of the vehicle wheel hub cover of FIG. 11;

FIG. 13 is a top view of the vehicle wheel hub cover of FIG. 11;

FIG. 14 is a bottom view of the vehicle wheel hub cover of FIG. 11;

FIG. 15 is a left side elevational view of the vehicle wheel hub cover of FIG. 11;

FIG. 16 is a right side elevational view of the vehicle wheel hub cover of FIG. 11;

FIG. 17 is a front elevational view of the vehicle wheel hub cover of FIG. 11;

FIG. 18 is a rear elevational view of the vehicle wheel hub cover of FIG. 11;

(Continued)

FIG. 19 is a cross-sectional view of the vehicle wheel hub cover of FIG. 11, sectioned along line 19-19 in FIG. 17; and, FIG. 20 is a cross-sectional view of the vehicle wheel hub cover of FIG. 11, sectioned along line 20-20 in FIG. 17. The broken lines in the drawings are for the purpose of illustrating portions of the vehicle wheel hub cover that form no part of the claimed design.
